UNITED STATES PATENT OFFICE

FRANCIS F. HAMILTON AND HAROLD E. VAN VOORHEES, OF INDIANAPOLIS,
INDIANA

EXHAUST MUFFLER

Application filed August 1, 1928. Serial No. 296,760.

This invention relates to mufflers for hydrocarbon motors and having for its primary objects a simple construction of parts so arranged that expansion and contraction due to heat will not loosen the several parts thereby preventing leakage of exhaust gases and rattling of parts; that minimizes instead of amplifying exhaust noises and eliminates overtones; that is supported by fire 5 resisting material to prevent transmission of vibrations through the muffler to the frame of the automobile or other structure carrying the motor and muffler; that is quiet and light in weight, and well adapted to 10 quantity production on punch and drawing presses; and that will prevent surging of gases from the motor, practically eliminating back pressure, and permit combustion of the carbon monoxide gases before leaving the 15 muffler.

These and other objects will become more apparent by the following description of the invention as illustrated in the accompanying drawings, in which—

Fig. 1 is a fragmentary side elevation of a muffler embodying our invention;

Fig. 2, a horizontal longitudinal section on the line 2—2 in Fig. 1;

Fig. 3, a vertical transverse section on the 20 line 3—3 in Fig. 1;

Fig. 4, a vertical transverse section on the line 4—4 in Fig. 1;

Fig. 5, a vertical transverse section through the tail pipe on the line 5—5 in Fig. 1;

Fig. 6, a fragmentary side elevation of the 25 exhaust head;

Fig. 7, a fragmentary front elevation of the exhaust head;

Fig. 8, a fragmentary side elevation of an 30 exhaust head slightly modified from that shown in Fig. 6;

Fig. 9, a fragmentary side elevation of an exhaust head further modified;

Fig. 10, a fragmentary rear elevation of the head shown in Fig. 9;

Fig. 11, a fragmentary side elevation of an exhaust head slightly modified from that shown in Fig. 9;

Fig. 12, a fragmentary side elevation of 50

a muffler modified in form from that shown in Fig. 1; and

Fig. 13, a horizontal longitudinal section on the line 12—12 in Fig. 13.

Like characters of reference indicate like 55 parts throughout the several views.

Referring first to Figs. 1 to 4 of the drawings, we form a muffler shell 15 having the upper portion substantially curved in cross-section on the line of an involute, so that a 60 cross-section through the shell appears in outline substantially as indicated in Figs. 3 and 4. The forward end of the shell 15 is curved around and tapered over to one side to form the extension 18 to receive an intake 65 pipe 16, and an inner wall 17 is spaced back of this forward extension 18 to retain therebetween a sound deadening material, preferably asbestos.

As will be noted in Figs. 1 and 2, the inner 70 wall 17 extends backwardly onto the shell 15 just enough to bring it parallel to the shell wall, so that gases coming around the wall 17 are discharged therefrom parallel to the wall of the shell 15.

A hollow body 19 is positioned within this extension 18 to have its apex within the inner end of the intake pipe 16 at the center thereof vertically but removed horizontally toward the side of the pipe 16, as in Fig. 2. This 80 body 19 is shaped to provide a passageway entirely therearound between it and the inner wall 17 of substantially equal width throughout its length. The rear of the body 19 is tapered into an apex lying substantially on 85 the horizontal center line of the shell 15, but removed a short distance from the vertical center line in the direction of the axis of the intake pipe 16. The forwardly directed face of the body is lined within preferably by asbestos held in place by the inner wall 20.

It is therefore to be seen, that gases coming through the intake pipe 16 strike the forward, inclined face of the body 19 and may escape through the passageway therearound, 95 some of the gases going the extreme short way "a" and some the varying longer distances past the body 19 up to the maximum way "b", so that the gases are in effect actually differentiated into streams of varying 100

lengths, permitting part of the gases to be delayed in arriving within the shell 15.

The rear end of the muffler shell 15 is enclosed by drawing the end around and inwardly forwardly to centrally receive therethrough the tail pipe 22.

The rear end of the shell 15 is so curved that gases striking the rear end from around the body 19 are deflected around and directed forwardly in lines parallel to the tail pipe 22.

The tail pipe 22 extends for a short distance to within the shell 15 where it is reduced in diameter to form a Venturi-like restriction from which it is flared outwardly and forwardly to form the metering head 23, which forms the support of the exhaust head generally designated by the numeral 24. The head 23 is provided with a plurality of slots 25 cut therethrough, the lower ends of the slots being spaced somewhat above the line of joinder of the head 23 with the pipe 22.

The forward end of the head 23 is enclosed by securing therein a hollow cone 26 with its apex directed backwardly toward the pipe 22, so that the only communication from the shell 15 to within the pipe 22 is through the slots 25. A hollow cone 27 is positioned by means of posts 28, Fig. 7, just in front of the cone 26 in a reversed position to have its apex directed forwardly and a frusto-conical apron 29 is secured to the periphery of the base of the cone 27 to extend backwardly and inwardly toward the pipe 22 to have its rear end terminate substantially in the plane of the restriction in the pipe 22 so that an annular opening is left for gases to escape from the shell 15 to within the passageway formed between the head 23 and the surrounding apron 29, this passageway being decreased in width from its opening to the end of the head 23 furthest removed from the pipe 22, discharging to within the space defined between the cones 26 and 27, which space operates as a sound trap, the gases having escaped laterally through the slots 25 in coming through this passageway.

In applying the muffler to some motors, it is found that better results are obtained as to reduction of noise by fixing a forwardly cupped visor 30 to the outside of the head 24, to have it extend toward the side of the shell, as in Figs. 1, 2, and 4, to which the intake pipe 16 is nearest. The characteristics of motors vary as to exhaust pressures, number of cylinders, size, etc., so that a wide range of noise and pressures are encountered in the exhaust discharge. Under some conditions, the tail pipe 22 is not restricted at the base of the head 23 as above described, but is kept at a uniform diameter as shown in Fig. 8, the head proper remaining the same as above described.

66 A modified form of exhaust head as shown

in Figs. 9, 10, and 11 gives good results. In this form, the tail pipe 22 is flared out on the forward end as in the head 24, having the pipe 22, either restricted at the base of the flare 31 as in Figs. 9 and 10, or maintained at full diameter as the conditions may require, as in Fig. 11. The flare 31 is provided with slots 32 therethrough and a hollow open base cone 33 with its apex forward is positioned in the forward end of the flare 31. About the flare 31, and spaced therefrom is a shell 34 having its rear end fixed to the pipe 22 and carrying on the forward end the hollow, open base cone 35 with its apex directed forwardly so that there is an opening over the forward end of the flare 31 into and between the cones 33 and 35.

A number of slots 36, here shown as three in number are cut through the shell 34 in the same plane near its junction with the cone 35 to permit gases from within the shell 15 to escape therethrough, and out the slots 32 into the tail pipe 22.

It is to be noted that the slots 25 in the form in Figs. 6, and 7 are V-shaped to have a gradually widening opening in the initial direction of the oncoming gases. Similarly, the slots 32 in the form in Figs. 9, 10 and 11 are reversed in position for the same reason. Attention is also directed to the fact, that in the form shown in Figs. 9, 10, and 11 that the slots 32 are only provided through the flare 31 under those portions of the shell 34 where there is no slot 36, there being no slots 32 through the flare 31 directly under the shell slots 36. As indicated in Fig. 10, holes 38 may be substituted for the slots 32 or the slots 25 in the first described form in Fig. 6.

Where cost of the muffler must be reduced to the minimum and some noise is not objectionable, the invention may be embodied in the form as shown in Figs. 12 and 13. Here the overall length of the muffler is shortened to give a short shell 40 having the same forward extension 18, but the body 19 is removed entirely and the exhaust head 24 brought up in its place, the head 24 tending to differentiate the incoming gases into different length streams, but not doing so quite as effectually as when the body 19 is employed.

Referring to Figs. 1 and 5, the muffler is suspended from the tail pipe by a short length of fabricated fire-resistant material 41, such as is commonly used for brake lining and the like. By such suspension, no vibrations in the muffler may be transmitted to the supporting frame 42.

While we have described our invention in the form now best known to us, it is obvious that many structural variations may be made without departing from the spirit of the invention, and we therefore do not desire to be limited to the precise form as shown

and described, nor any more than may be required by the following claims.

We claim:

1. In an exhaust gas muffler, a shell closed at both ends, an intake pipe entering the front end, a tail pipe extended through the rear end, an exhaust head carried on the forward end of the tail pipe in the shell, said shell and front end of the muffler being shaped to give a longer distance across the end and along one side of the shell than on the opposite side with gradually decreasing distances therebetween, said rear end being curved from the shell around and forwardly whereby gas flowing backwardly along the shell wall will be reversed in direction of flow to be directed forwardly toward said exhaust head.

2. In an exhaust gas muffler, a shell closed at both ends, an intake pipe entering the front end, a tail pipe extending through the rear end, an exhaust head carried on the forward end of the tail pipe in the shell, said shell and front end of the muffler being shaped to give a longer distance across the end and along one side of the shell than on the opposite side with gradually decreasing distances therebetween, said rear end being curved from the shell wall around and forwardly whereby gas flowing backwardly along the shell wall will be reversed in direction of flow to be directed forwardly toward said exhaust head, and a deflector body carried in said front end to define a passageway therearound between it and the end wall, said passageway discharging into said shell parallel to the shell wall.

3. In an exhaust gas muffler, a shell closed at both ends, an intake pipe entering the front end, a tail pipe extending through the rear end, an exhaust head carried on the forward end of the tail pipe in the shell, said shell and front end of the muffler being shaped to give a longer distance across the end and along one side of the shell than on the opposite side with gradually decreasing distances therebetween, said rear end being curved from the shell wall around and forwardly whereby gas flowing backwardly along the shell wall will be reversed in direction of flow to be directed forwardly toward said exhaust head, and a deflector body carried in said front end to define a passageway therearound between it and the end wall, said passageway discharging into said shell parallel to the shell wall, said front end and the forward side of said deflector body being lined with sound deadening material.

4. In an exhaust gas muffler, a shell closed at both ends, an intake pipe entering the front end, a tail pipe extending through the rear end, an exhaust head carried on the forward end of the tail pipe in the shell, said shell and front end of the muffler being

shaped to give a longer distance across the end and along one side of the shell than on the opposite side with gradually decreasing distances therebetween, said rear end being curved from the shell wall around and forwardly whereby gas flowing backwardly along the shell wall will be reversed in direction of flow to be directed forwardly toward said exhaust head, and a deflector body carried in said front end to define a passageway therearound between it and the end wall, said passageway discharging into said shell parallel to the shell wall, and a deflector on said exhaust head extending therefrom toward the side of the shell having the shortest gas travel therealong.

5. In an exhaust gas muffler, a shell closed at both ends, an intake pipe entering the front end, a tail pipe extending through the rear end, an exhaust head carried on the forward end of the tail pipe in the shell, said shell and front end of the muffler being shaped to give a longer distance across the end and along one side of the shell than on the opposite side with gradually decreasing distances therebetween, said rear end being curved from the shell wall around and forwardly whereby gas flowing backwardly along the shell wall will be reversed in direction of flow to be directed forwardly toward said exhaust head, and a deflector body carried in said front end to define a passageway therearound between it and the end wall, said passageway discharging into said shell parallel to the shell wall, said front end and the forward side of said deflector body being lined with sound deadening material.

6. In an exhaust gas muffler, a tail pipe, and an exhaust head adapted to discharge into said tail pipe, said head comprising an inner frustro-conical wall having apertures therethrough, said wall flaring outwardly and away from said tail pipe, a closure across the base of said wall, and a second outer frustro-conical wall surrounding and having less slope than that of said first wall, the end of said second wall toward said tail pipe being open and spaced outwardly therefrom whereby an annular passageway about said first wall is formed therebetween diminishing in volume toward the base of said first wall.

7. In an exhaust gas muffler, a tail pipe, and an exhaust head adapted to discharge into said tail pipe, said head comprising an inner frustro-conical wall having apertures therethrough, said wall flaring outwardly and away from said tail pipe, a closure across the base of said wall, and a second outer frustro-conical wall surrounding and having less slope than that of said first wall, the end of said second wall toward said tail pipe being open and spaced outwardly therefrom whereby an annular passageway about said first wall is formed therebetween diminishing in volume toward the base of said first

wall, said apertures comprising V-shaped openings having their widestmost sections directed toward the base of said first wall.

8. In an exhaust gas muffler, a tail pipe, and an exhaust head adapted to discharge into said tail pipe, said head comprising an inner frustro-conical wall having apertures therethrough, said wall flaring outwardly and away from said tail pipe, a closure across the base of said wall, and a second outer frustro-conical wall surrounding and having less slope than that of said first wall, the end of said second wall toward said tail pipe being open and spaced outwardly therefrom whereby an annular passageway about said first wall is formed therebetween diminishing in volume toward the base of said first wall, and a housing spaced from said closure and joining with the annular base of said second wall to define an annular opening between said first wall and said second wall discharging into said housing.

9. In an exhaust gas muffler, a tail pipe, and an exhaust head adapted to discharge into said tail pipe, said head comprising an inner frustro-conical wall having apertures therethrough, said wall flaring outwardly and away from said tail pipe, a closure across the base of said wall, and a second outer frustro-conical wall surrounding and having less slope than that of said first wall, the end of said second wall toward said tail pipe being open and spaced outwardly therefrom whereby an annular passageway about said first wall is formed therebetween diminishing in volume toward the base of said first wall, and said closure being cone-shaped and extending to within said first frustro-conical wall.

10. In an exhaust gas muffler, a muffler shell having a rear end, a tail pipe through said rear end, an exhaust head on the forward end of the tail pipe within the shell, said exhaust head having a plurality of V-shaped slots extending longitudinally of the head with their broad ends toward the front of the head.

In testimony whereof we affix our signatures.

FRANCIS F. HAMILTON.
HAROLD E. VAN VOORHEES.
